RAILWAY TRACK CIRCUIT APPARATUS

Norman F. Agnew, Penn Township, Allegheny County, Pa., assignor to The Union Switch & Signal Company, Swissvale, Pa., a corporation of Pennsylvania

Application January 8, 1942, Serial No. 426,055

13 Claims. (Cl. 246—3)

My invention relates to railway track circuit apparatus, and it has particular reference to the organization of such apparatus into railway track circuits of the double track circuit class wherein energy is transmitted from one end of a section through the track rails to the opposite end for effecting a control or controls and other energy is transmitted from the opposite end of a section through the track rails to the one end for effecting another control or other controls. More particularly, my invention relates to double track circuits wherein one of the track circuits is of the impulse type shown for example in Letters Patent of the United States No. 2,178,806, granted on November 7, 1939 to Willard P. Place and Andrew J. Sorensen.

In an impulse type of track circuit, the track rails are supplied with relatively high voltage impulses of energy of relatively short duration, which impulses are separated from each other by relatively long intervals during which no energy is present in the track rails. The impulses are detected by suitable translating apparatus, and means may be provided for effecting different controls according to the code rates of occurrence of the impulses, or to the relative polarity of such impulses, or to a combination of these as well as other characteristics of the impulses. The translating apparatus includes a winding connected to the rails for energization by the impulses and contact means operated by such energized winding, while the impulses are transmitted by means comprising a winding connected to the rails at the opposite end of a section and inductively coupled with another winding periodically energized over a coding contact for creating a flux which collapses rapidly each time the coding contact opens. This rapid collapse or decay of flux causes a relatively high voltage peak of short duration to be transmitted from the inductively coupled winding to the track rails, and each of these voltage peaks causes operation of the contact means of the translating apparatus, provided of course that the section is unoccupied.

Circuits of this class customarily are employed for effecting a control or controls in the rear of trains operating on the signaled stretch, and heretofore it has been proposed to utilize, in combination with these impulse type track circuits, line wire control to effect a control or controls in advance of trains on the stretch. However, the organization of the apparatus providing an impulse type of track circuit is such that the energy source for the voltage peaks is insulated from the contact means operated thereby by

means of the windings employed at the ends of the section. In other words, the circuit is arranged to be energized from a secondary source of energy inductively coupled but insulated from direct connection with the primary source. It is, therefore, an object of my invention to utilize this closed circuit insulated from the primary winding of the peak voltage impulses, to transmit energy from the track relay or entrance end of the section to the opposite or exit end of the section for effecting a control or controls in advance of trains operating on the stretch.

Another object is to provide a novel and improved arrangement of double track circuits for effecting controls both in the rear and in advance of traffic on a stretch.

A further object is to provide novel and improved means for incorporating approach control means in an impulse type track circuit.

A further object is to provide novel and improved means for reducing the energy consumption of a signal system incorporating impulse type track circuits.

A further object is to provide novel and improved track circuit arrangements.

In practicing my invention, the above-mentioned and other important objects and characteristic features which will become readily apparent from the following description are attained by incorporating a second source of energy and a second winding into the closed circuit track circuit arrangement by means of which an impulse type track circuit is provided. The second source of energy is interposed in series with a winding of the impulse translating device, while the second winding is interposed in series with the winding that serves as the secondary source of energy for the impulse transmitting means. The second winding is provided with contacts which it operates in response to energy received from the second source but not in response to the impulses of relatively high peak voltages that are transmitted from the serially connected winding of the impulse transmitting means.

I shall describe several forms of apparatus embodying my invention, and shall then point out the novel features thereof in claims.

In the accompanying drawing, Fig. 1 is a diagrammatic view illustrating one form of apparatus embodying my invention. Fig. 2 is a diagrammatic view illustrating a modified form of the apparatus represented in Fig. 1 and also embodying my invention. In each of the two views, similar reference characters have been employed to designate corresponding parts.

According to the invention, a railway track circuit of the impulse type is provided with a reverse circuit arranged to be effective to exert a control in advance of a train on the section. This reverse circuit may be utilized for controlling any desired function such as the illumination of signal lamps upon approach of a train to a signal, or the operation of a highway crossing signal at a railway-highway intersection, etc. In one embodiment of my invention, represented in Fig. 1, the reverse circuit is employed to effect approach lighting of signals and is applied to a stretch of single track railroad over which traffic operates in the direction indicated by an arrow or from right to left as viewed in the drawing. The track rails 1 and 1a are divided by insulated joints 2 into a plurality of successive adjoining track sections of which only one section, D-E, is shown complete in the drawing. Section D-E is provided with an impulse type track circuit of the class illustrated and described in detail in the aforesaid Patent No. 2,178,806, and which track circuit has incorporated therein means for additionally providing the section with a second or reverse track circuit. These track circuit means include impulse transmitting means at one end of the section and impulse translating means at the opposite end of the section.

The impulse transmitting means, as shown, comprise a track transformer TT having a primary winding 4 periodically supplied with unidirectional current from any suitable source, such as from a battery not shown but having its opposite terminals designated by the reference characters B and C, each time a contact 5-6 is operated by a contact operating device CT is closed. The device CT may be, for example, a code transmitter which is arranged to operate its contacts 5-6 at a selected rate of, say, 60 times per minute. Primary winding 4 of transformer TT has connected in multiple therewith a condenser 7 arranged to control the time constant of the circuit so as to cause the current in the winding to build up gradually and reach its steady state value at substantially the end of each interval that contact 5-6 is closed. This energy in winding 4 creates a flux which collapses or decays rapidly each time contact 5-6 opens, and this rapid collapse of flux induces a voltage impulse of relatively large magnitude in secondary winding 8 of transformer TT. Winding 8 is connected in series with the operating winding of a relay, designated by the reference character AR with a suitably distinguishing suffix, across the track rails 1 and 1a at the exit end of section D-E, and preferably, there is connected in multiple with the winding of relay ARD an asymmetric unit 9 poled in a direction to be made clear presently so as to shunt current of a given relative polarity away from relay ARD.

The impulse translating means at the opposite or entrance end of section D-E comprises a winding 10 provided with contact means operated thereby, and a source of unidirectional current such as a battery 11, connected in series across the track rails 1 and 1a at the entrance end of section D-E. Winding 10 preferably has connected in series therewith an asymmetric unit 12 poled in opposition to the flow of current from battery 11, and connected in multiple with winding 10 and unit 12 is a resistor 13 and an asymmetric unit 14 poled to permit the flow of current from the battery.

The winding 10 represented in Fig. 1 comprises the operating winding of a relay, designated by

the reference character TR with a suitably distinguishing suffix, and preferably of the biased polar neutral type. Relay TRE has a contact member which is biased to a normal, or left-hand position as illustrated in the drawing, and which contact member is caused to operate to its other or right-hand position in response to energization of its operating winding by a voltage impulse of a given relative polarity. Operatively associated with contact 15 are signal control means, designated by the reference character 16. The details of such control means are not shown in the present case, but these means may be similar, for example, to the means shown in the aforesaid Patent No. 2,178,806, associated with the contacts of the impulse operated track relay of the patent.

Associated with each section adjacent its entrance end is a traffic controlling signal, designated by the reference character S with a suitably distinguishing suffix. Each signal S is selectively controlled by the impulse translating means of its associated section, in a manner indicated in the drawing but not shown since the details of such control are well known and form no part of the present invention. Each signal S is, however, normally inactive, that is, normally non-illuminated, and becomes illuminated to display an active indication or aspect only upon release of the approach lighting relay AR incorporated into the track circuit apparatus of the section next in the rear. Signal SD, for example, may be supplied with illuminating or activating energy when and only when back contact 18 of relay ARD, associated with section D-E in the rear of signal SD, is closed to complete an obvious circuit for lamp L of the signal.

The apparatus represented in Fig. 1 is in its normal condition, as represented in the drawing, when section D-E and the adjacent rear and advance sections are unoccupied. In this condition of the apparatus, relay ARD of section D-E is held up by energy supplied over a circuit which extends from one terminal of battery 11 through asymmetric unit 14 in its low resistance direction, resistor 13, rail 1a, winding 8 of transformer TT, the winding of relay ARD, rail 1, and the other terminal of battery 11. This energy is blocked from passing through track relay TRE due to asymmetric unit 12 which presents its high resistance direction to the flow of energy from the battery. Relay ARD accordingly is held up by energy from battery 11, but this energy has no effect or influence on track relay TRE. Track relay TRE responds, however, to relatively high peak voltage impulses caused to be transmitted from winding 8 due to the periodic energization of its inductively coupled winding 4. That is to say, each time contact 5-6 of coder CT closes, unidirectional energy is supplied to winding 4 and slowly builds up to its steady state value. At such time, there is relatively little if any inductive transfer of energy to winding 8, due to the relatively slow rate of change of flux in the transformer. When, however, contact 5-6 opens, the flux in the transformer rapidly collapses and the parts of the transformer are so arranged to cause a relatively high impulse having a given relative polarity, indicated in the drawing by the reference marks + and -, to be induced in winding 8. This impulse is transmitted to relay TRE over a circuit which extends from one terminal of transformer TT through rail 1a, winding 10 of relay TRE, asymmetric unit 12 in its low resistance direction,

battery 11 in opposition to its electromotive force, rail 1, and asymmetrical unit 9 in its low resistance direction to the other terminal of winding 8. Each voltage impulse is thus shunted away from approach lighting relay ARD due to the low resistance path of asymmetrical unit 9, hence such relay is not influenced by the impulses transmitted from winding 8 and furthermore the relay does not materially influence the shape or wave form of such impulses. The impulses are of the proper relative polarity to cause track relay TRE to operate its contact members, hence the signal control means associated therewith are normally conditioned to cause the associated signal SE to indicate that section D—E is unoccupied. Signal SE is, however, inactive or deenergized since the energizing circuits thereof are deenergized due to back contact 18 of relay ARD being opened.

When a train occupies the section in the rear of section D—E, relay ARD is caused to release and close its back contact 18 to render signal SE active and capable of displaying an illuminated indication. Both relays TRE and ARD are shunted when the train enters section D—E, hence signal SD becomes approach lighted while the signal control apparatus associated with signal SE conditions that signal to display its "block occupied" indication. After the train vacates the section in the rear of section D—E, relay ARD picks up to deenergize signal SE, and after the train vacates section D—E, both relays ARD and TRE become energized and the track circuit apparatus of section D—E is restored to its normal condition, as represented in the drawing.

The impulse track circuits represented in Fig. 1 are normally energized, as is the customary practice. Under certain conditions, it may be desirable to arrange the circuits to be normally deenergized, and provide means manually controllable for energizing the circuits as desired. The apparatus illustrated in Fig. 2 represents one arrangement whereby normally deenergized track circuits of the impulse type may be energized at will by manually operable means. Referring to Fig. 2, the reference character LHSR designates a signal control relay manually controllable from a remote point in any suitable manner, as by means of a communication or centralized traffic control system such as is shown, for example, in the Lewis Patent No. 2,197,130, granted April 16, 1940, for Remote control apparatus. For the purposes of the present description it is deemed sufficient to state that relay LHSR is normally released, and that its front contact 21 is normally opened to disconnect terminal B from primary winding 4 of transformer TT. Under such conditions, no energy is applied to transformer TT even though contacts 5 and 22 of coder CT may be intermittently closed and opened, hence no voltage impulses are caused to be transmitted from secondary winding 8 and as a result the track relay TR is caused to retain its contact member 15 in its biased normal position. Relay TR may be directly interposed in the circuit connection of battery 11 to the track rails of the section, as illustrated in Fig. 1, or as shown in Fig. 2 (see relay TRE), the relay may be inductively coupled with the track circuit by means of a receiving transformer RT having a secondary winding 23 connected to relay TRE and having its primary winding 10 connected in series with battery 11 to the rails 1 and 1a. In this latter case, battery 11 feeds current through winding 10 of transformer RT, but this current

has little if any effect upon relay TRE, since it is unidirectional in character and hence does not cause an inductive transfer of energy to the relay. The arrangement may also involve additional checking apparatus comprising a checking relay CR and a time element relay TE, shown for example in Fig. 2 associated with relay TRE.

The impulse track circuits illustrated in Fig. 2 are arranged to effect different controls according to the relative polarity of the voltage impulses applied to the circuits. The track relays employed in Fig. 2 accordingly are of the type having a polar armature biased to a center or mid position, and operable to either one or the other of two extreme positions according as the operating relay winding is energized by current of one relative polarity or the other. Each track relay has associated therewith signal control means comprising two control relays NC and PC, but only the two control relays associated with relay TRD are illustrated in the drawing. Relay NC is connected through a full-wave rectifier 24 to secondary winding 25 of a transformer DT1, while relay PC is connected through another rectifier 24 to secondary winding 25 of another transformer DT2. The primary winding 26 of transformer DT1 is supplied with unidirectional current each time armature 15 of relay TRD operates to its left-hand position (as viewed in Fig. 2) and hence relay NC is supplied with energy inductively transmitted from winding 26 each time contact 15 of relay TRD is caused to assume its left-hand position due to the energization of such relay by voltage impulses having a given relative polarity, hereinafter assumed to be of negative polarity. Similarly, the primary winding 26 of the other transformer DT2 is supplied with unidirectional energy each time contact 15 of relay TRD is caused to operate to its right-hand position in response to energization of the relay by energy of the opposite or positive polarity. The relays NC and PC are arranged to be effectively energized and picked up when supplied with energy impulses from their associated transformers at the predetermined code rate hereinbefore assumed to be 60 cycles per minute, hence it follows that when relay TRD responds to voltage impulses of negative polarity, relay NC is picked up; when relay TRD responds to voltage impulses of positive polarity, relay PC is picked up; and when relay TRD responds alternately to voltage impulses of first negative and then positive polarity, both relays NC and PC are picked up.

Relays NC and PC cooperate with relays LHSR and ARD in controlling the associated wayside signal SD, in the following manner. When relay ARD is released, its back contact 18 is closed and energy is then applied to the signal control circuits hereinafter described, thereby conditioning the associated signal to display an active or illuminated indication. When relay ARD is picked up, however, energy is removed from the signal control circuits and as a result the associated signal is dark or inactive. When relay LHSR is released, the proceed indication lamps of the associated signal are placed on open circuit and such lamps accordingly cannot become energized to display an illuminated or active indication. These lamps may, however, be energized if relay LHSR is picked up to close its front contact 28. The most restrictive or stop aspect of the wayside signal, however, may be energized if relay LHSR is released, over a circuit extending from terminal B through back-contact 18 of relay ARD, back contact 29 of relay PC, back contact 30 of

relay NC, and the filament of lamp 31 of signal SD to terminal C. Signal SD accordingly is conditioned to display its stop aspect when both control relays NC and PC are released. When relay NC is picked up and relay PC is released, the signal is then conditioned to display an approach indication, over a circuit which includes the filament of lamp 32, front contact 30 of relay NC and back contact 29 of relay PC, and which circuit is completed when front contact 28 of relay LHSR and back contact 18 of relay ARD are closed. When relay PC is picked up but relay NC is released, signal SD is then conditioned to display an approach restricting indication, over a circuit which includes front contact 28 of relay LHSR, the filament of lamp 33 of signal SD, back contact 35 of relay NC, front contact 29 of relay PC, and back contact 18 of relay ARD. Signal SD is conditioned to display its clear aspect when both relays NC and PC are picked up to prepare a circuit which includes back contact 18 of relay ARD, front contact 29 of relay PC, front contact 35 of relay NC, the filament of lamp 34 of signal SD, and front contact 28 of relay LHSR.

The control relays NC and PC cooperate in controlling the polarity of voltage impulses impressed on the track circuit of the section next in the rear. As pointed out hereinbefore, impulse track circuit energy is removed from a section unless the remotely controlled relay LHSR associated therewith is picked up to close its front contact 21. When this happens, the section in the rear is supplied with voltage impulses of negative polarity when both relays NC and PC of the section in advance are released; is supplied with voltage impulses of positive polarity if relay NC is picked up but relay PC is released; and is supplied with voltage impulses of alternately negative and positive polarity if relay PC is picked up, or if both relays NC and PC are picked up.

Voltage impulses of negative polarity are caused to be transmitted from transformer TT to the rails of section D—E when relay LHSR is picked up and relays NC and PC are both released to complete a circuit extending from terminal B through front contact 21 of relay LHSR, back contact 31 of relay NC, back contact 38 of relay PC, contact 39—22 (when closed) of coder CT, primary winding 4 of transformer TT, and contact 5—40 (when closed) of coder CT. Each time contact members 5 and 22 of coder CT engage their respective contact points 40 and 39, unidirectional energy is supplied to winding 4 and traverses that winding in one direction to set up a flux of a given direction, which flux collapses rapidly when the coder contacts open and cause a voltage impulse of a given relative polarity (assumed to be negative polarity) to be transmitted from winding 8 to the track rails. When relays LHSR and NC are picked up, there is established a circuit extending from terminal B through front contact 21 of relay LHSR, front contact 31 of relay NC, back contact 42 of relay PC, contact 6—5 (when closed) of coder CT, winding 4, and contact 22—41 (when closed) of coder CT to terminal C. Each time the coder contacts 5 and 22 engage their respective contact points 6 and 41, unidirectional energy is caused to traverse winding 4 in the direction opposite that of energy supplied when both relays NC and PC are released, hence flux of the opposite direction is created in transformer TT, and each time the coder contacts open, a voltage impulse of the opposite (or positive) polarity is caused to be transmitted to the track rails. When relays

LHSR and PC are both picked up, unidirectional energy is supplied to winding 4 first in one direction, over front contact 38 of relay PC, when coder contacts 39—22 and 5—40 are closed, and then in the other direction over front contact 42 of relay PC each time coder contacts 6—5 and 22—41 are closed. It follows, therefore, that whenever relay PC, or both relays NC and PC are picked up, voltage impulses of alternately first one and then the other relative polarity are caused to be transmitted from transformer TT to the track rails.

The approach lighting relay ARD may be employed not only for providing approach lighting of the wayside signal, as mentioned hereinbefore, but may also be employed as a detector track relay for providing information as to whether the associated section is or is not occupied. That is to say, relay ARD may be employed to cause the communication system to transmit an indication code to the office each time the relay operates from either position to the other. When relay ARD picks up, its front contact 45 closes and this contact may condition the station equipment, in a well-known manner, to transmit to the office an indication relating to an unoccupied section, and each time relay ARD releases, its back contact 45 closes and may condition the station equipment to transmit to the office an indication code relating to an occupied section.

The apparatus of Fig. 2 is in its normal condition, as represented in the drawing, when section D—E and the section in advance are unoccupied, relay LHSR is released, and the impulse track circuit of the advance section is deenergized. In this condition of the apparatus, relay ARD is held energized by current supplied from battery 11, but relay TRE is inactive since the impulse track circuit is deenergized. Under the conditions assumed, signal SD is conditioned to display its stop aspect, and will do so should a westbound train enter the section to shunt relay ARD and cause its back contact 18 to complete the previously traced circuit for lamp 31 of signal SD. The release of relay ARD at this time will cause an occupied section indication code to be transmitted to the office by the communication system. The operator will therefore be informed of the presence of the train on section D—E, even though the impulse track circuits employed for governing the train movement are deenergized. Should the train vacate section D—E, relay ARD then will pick up and cause the communication system to transmit an unoccupied section code to the office to indicate that section D—E is vacant.

If, however, section D—E remains cleared, and the operator wishes to authorize a westbound train to proceed over the stretch, he will suitably control the communication system to cause the signal control stick relays LHSR to pick up. When this happens, the signal control relays NC and PC associated with the section in advance of section D—E will be controlled according to the type of energy causing operation of the associated track relay TRD. I shall assume that this energy is of the clear code type comprising voltage impulses of alternately positive and negative polarity. Under the assumed conditions, both relays NC and PC will be picked up; voltage impulses of alternately positive and negative polarity will be applied to the rails of section D—E; and signal SD will be conditioned to display its clear aspect. When a westbound train enters section D—E, and shunts current from battery 11 away from relay ARD, the signal will then dis-

play its active or illuminated clear aspect; and the communication system will be conditioned to transmit the occupied section indication code to the office.

When the train enters the section in advance of section D—E, relay TRD is shunted and both control relays NC and PC are released, thereby conditioning signal SD to display its illuminated stop aspect. After the train vacates section D—E, voltage impulses of negative polarity are impressed on the track rails and cause response of the associated relay TRD. Relay ARD also picks up to remove energy from the signal control circuits, thereby causing signal SD to become dark; and also to cause the communication system to transmit to the office the unoccupied section code.

When the section in advance becomes vacated and relay TRD responds to voltage impulses of negative polarity, relay NC picks up to cause the impulse transmitting apparatus of section D—E to supply impulses of positive polarity to the associated track rails, and also to condition signal SD to display its approach aspect. Signal SD is conditioned to display its approach restricting aspect when relay PC is picked up and relay NC is released due to relay TRD responding to voltage impulses of positive polarity applied to the section in advance of section D—E when the train vacates the second section in advance of section D—E. With relay PC picked up, the impulse transmitting apparatus of section D—E is caused to apply voltage impulses of alternately negative and positive polarity to the rails of the section.

When three or more sections in advance of section D—E are unoccupied, relay TRD is caused to respond to voltage impulses of alternately positive and negative polarity, and both relays NC and PC associated therewith are picked up to condition signal SD to display its clear aspect, and also to cause voltage impulses of alternately positive and negative polarity to be impressed on the rails of section D—E.

The apparatus of Fig. 2 may be restored to its normal condition by the operator causing a suitable control to be transmitted over the communication system to cause the signal control relay LHSR to be released. When this happens, energy is removed from the impulse track circuits whereupon the track relays TR become inactive; the associated control relays become released; and the associated signals S are conditioned to display their respective stop aspects should a train enter their associated sections under the conditions assumed.

The impulse translating arrangement involving track relay TRD of Fig. 2 might be subject to a false operation should a loose connection of battery 11 to the track rails exist. This loose connection, when vibrated as by the passage of a train, might cause an inductive transfer of energy from battery 11 to relay TRD, and thereby cause an operation of the relay so as to give a false approach indication to a following train. The possibility of such a false indication is very remote, but should it be desired to guard against such a possibility, the arrangement involving track relay TRE of Fig. 2 represents a typical method for preventing a false proceed indication due to a break in the connection of battery 11 to the track rails.

The impulse translating apparatus involving track relay TRE of Fig. 2 is represented as including a relay CR having its winding connected, over its own front contact 48, in series with battery 11 and winding 10 across the rails 1 and 1a. Relay

CR is adjusted to be normally energized regardless of whether the associated section is occupied or unoccupied, and releases only in the event that the circuit connection of battery 11 to the rails becomes interrupted. When this happens, relay CR opens its front contact 48 and places battery 11 on open circuit, thereby avoiding any possibility that a loose connection vibrated alternately open and closed might cause unauthorized response of relay TRE. When relay CR releases, a time element device TE, such as a thermal relay, becomes energized over an obvious circuit including battery 11, back contact 48 of relay CR, and the operating element 49 of time element device TE. At the end of the predetermined time interval of the device, its contact 50 closes to complete a circuit path including back contact 48 of relay CR and contact 50 of device TE, which path connects relay CR and battery 11 to the track rails in a pick-up circuit. Should the connection of relay CR and battery 11 to the track rails be open due to a break in the circuit connection, relay CR of course will remain released to maintain device TE energized, until the break has been repaired. Should, however, the broken connection be of the type that is intermittently vibrated open and closed, relay CR might pick up during the interval that the circuit connection is vibrated closed, thereby deenergizing device TE, but after contact 50 of the device opens, relay CR will release during the interval that the circuit connection is vibrated open, and battery 11 again will be placed on open circuit, and device TE again will be energized. This cycle of operation will be repeated as long as the intermittently closed broken connection exists in the apparatus, but of course relay TRE will be affected only momentarily if at all, hence the relay will remain inactive and a display of a false proceed indication will be prevented.

From the foregoing description, it is readily apparent that I have provided novel and improved track circuit apparatus of the double track circuit type wherein one of the circuits is of the impulse type. It is also apparent that I have provided means whereby traffic on the stretch may be safely governed even though one of the track circuits is normally deenergized and is manually controllable to authorize a train movement at the will of an operator. In addition, it is apparent that the apparatus may be arranged to insure against a false operation of the apparatus should a broken connection exist in the impulse translating means.

Although I have herein shown and described only a few forms of railway track circuit apparatus embodying my invention, it is understood that various changes and modifications may be made therein within the scope of the appended claims without departing from the spirit and scope of my invention.

Having thus described my invention, what I claim is:

1. In combination, a section of railway track, a first source of energy, a first relay means having a first winding connected in series with said first source to the rails at one end of said section, said first relay means having contacts biased to a normal position wherein they are held when said first winding is steadily energized by current from said first source but which contacts are operated away from said normal position when said first winding is intermittently supplied with impulses of energy, and means for intermittently impressing energy on said track rails at the opposite end of said section, said means comprising a second

winding and a second relay connected in series to the rails at said opposite end of said section, said second relay being so constructed as to be immune to impulses of energy from said winding, a second source of energy at said opposite end of said section, contact means having a contact periodically opened and closed, and another winding inductively coupled with said second winding and supplied with energy from said second source when said contact is closed for creating flux effective each time said contact is opened for causing an impulse of energy to be induced in said second winding.

2. In combination, a section of railway track, a track transformer, a circuit for the primary winding of said transformer including a source of unidirectional energy and a contact periodically closed for periodically energizing said winding and effective each time when opened for causing the induction of an impulse of current in the secondary winding of said transformer, a relay connected in series with said secondary winding to the rails at one end of said section, said relay being so constructed as to be immune to impulses induced in said secondary winding, a second source of unidirectional energy for energizing said relay, another winding connected in series with said second source to the rails at the opposite end of said section, and contacts operated by means responsive to the energization of said other winding effected by said current impulses but not by the steady supply of energy from said second source.

3. In combination, a section of railway track, a track transformer, a circuit for the primary winding of said transformer including a source of unidirectional energy and a contact periodically closed for periodically energizing said winding and effective each time when opened for causing the induction in the secondary winding of said transformer of an impulse of current having a given relative polarity, a relay connected in series with said secondary winding to the rails at one end of said section, said relay being so constructed as to be immune to impulses induced in said secondary winding, a second source of unidirectional energy for energizing said relay, a winding connected in series with said second source to the rails at the opposite end of said section with said second source poled in opposition to current impulses from said transformer, and contacts operated by means responsive to the energization of said other winding effected by said current impulses but not by the steady supply of energy from said second source.

4. In combination, a section of railway track, a track transformer having a primary winding periodically supplied with unidirectional energy, a relay connected in series with the secondary winding of said transformer to the rails at one end of said section, a receiving transformer having a secondary winding connected to a track relay, a source of unidirectional energy connected in series with the primary winding of said receiving transformer to the rails at the opposite end of said section, and signal control means operated by said track relay in response to energy derived from the secondary winding of said receiving transformer.

5. In combination, a section of railway track, a source of unidirectional energy, a first relay means having a first winding connected in series with said source to the rails at one end of the section, said first relay means being responsive only to energization of said first winding effected

by energy intermittently impressed on said track rails at the opposite end of said section, a second winding and a second relay connected in series to the rails at said opposite end of said section, said second relay being responsive only to energy from said first source, a second source of unidirectional energy, contact means having a contact periodically closed and opened, a third winding inductively coupled with said second winding, a

10 remotely controlled relay, means controlled by said remotely controlled relay and said contact of said contact means for at times supplying energy from said second source to said third winding for creating flux effective each time said contact opens to cause the induction in said second winding of a relatively high peak voltage impulse.

6. In combination with a section of railway track, an impulse type track circuit for said section comprising impulse translating means connected to the rails at one end and impulse transmitting means connected to the rails at the other end of said section, a reverse track circuit for said section comprising a source of energy connected to the rails at said one end and a track relay connected to the rails at said opposite end of said section, a control office at a remote point, a communication system extending from said control office to a station adjacent to said section, a control relay at said station manually controllable from said office over said communication system, means controlled by said control relay for causing said impulse transmitting means to be effective or ineffective to transmit impulses at the will of an operator at said office, a signal governing traffic in advance of said section, and means controlled by said track relay for approach energizing said signal when said section becomes occupied.

7. In combination with a section of railway track, an impulse type track circuit for said section comprising impulse translating means connected to the rails at one end and impulse transmitting means connected to the rails at the other end of said section, a reverse track circuit for said section comprising a source of energy connected to the rails at said one end and a track relay connected to the rails at said opposite end of said section, a control office at a remote point, a communication system extending from said control office to a station adjacent to said section, a control relay at said station manually controllable from said office over said communication system, means controlled by said control relay for causing said impulse transmitting means to be effective or ineffective to transmit impulses at the will of an operator at said office, and means governed by said track relay for causing said communication system to transmit indications relating to traffic conditions in said section.

8. In combination with a section of railway track, a source of unidirectional energy and an impulse responsive relay coupled to the track rails at one end of said section, said relay being non-responsive to energy from said source, a second source of energy and a second relay, a circuit including the winding of said second relay for inductively coupling said second source of energy to the rails at the opposite end of said section, means for causing said circuit to transmit impulses of relatively high peak voltage to said track rails, a control office at a remote point, a communication system extending from said office to a station adjacent to said section, a control relay at said station manually controllable from said office over said communication system,

means governed by said control relay for causing said circuit to be effective or ineffective to transmit impulses to the rails at the will of an operator at said office, and means governed by said track relay for causing said communication system to transmit to said office information relating to traffic conditions in said section.

9. In combination with a section of railway track, a source of unidirectional energy and an impulse responsive relay coupled in circuit to the track rails at one end of said section, said relay being non-responsive to energy from said source, a second source of energy and a second relay, a circuit including the winding of said second relay for inductively coupling said second source of energy to the rails at the opposite end of said section, means for causing said circuit to transmit impulses of relatively high peak voltage to said track rails, a control office at a remote point, a communication system extending from said office to a station adjacent to said section, a control relay at said station manually controllable from said office over said communication system, means governed by said control relay for causing said circuit to be effective or ineffective to transmit impulses to the rails at the will of an operator at said office, a signal governed by said impulse responsive relay for authorizing traffic movements in said section when said relay responds to said high peak voltage impulses, and means governed by said track relay for causing said communication system to transmit to said office information relating to traffic conditions in said section.

10. In combination, a section of railway track having a relay connected in series with a secondary winding to the rails at one end of said section, a primary winding intermittently supplied with energy and inductively coupled with said secondary winding, said relay being non-responsive to energy induced in said secondary winding, a source of energy for energizing said relay, a control relay, a checking relay; a circuit including said source, a front contact and the winding of said checking relay for inductively coupling said control relay to the rails at the opposite end of said section; said control relay being responsive to energy induced in said secondary winding, a time element relay, an energizing circuit for said time element relay including a source of energy and a back contact of said checking relay, and a circuit path including an operated contact of said time element relay for providing a shunt path around said front contact of said checking relay in said circuit of said control relay.

11. In combination with a section of railway

track, a source of current, a control relay, a checking relay, a circuit including said source and a front contact and the winding of said checking relay for inductively coupling said control relay to the rails of said section, a time element relay energized over a circuit including a back contact of said checking relay, said time element relay having a time contact which becomes closed at the end of a predetermined time interval of energization of said relay, and a circuit path including said time contact for providing an alternative path around the front contact of said checking relay in said circuit of said control relay.

12. In combination with a section of railway track, two batteries, a first relay, a circuit including the winding of said first relay for inductively coupling one of said batteries to the track rails at one end of said section, another relay, a circuit connecting in series the winding of said other relay and the other of said batteries to the track rails at the other end of said section, said other battery being orientated to oppose the electromotive force inductively applied to the track rails from said one battery, an asymmetrical unit connected in multiple with said other relay and poled to shunt current from said other battery away from said other relay, and another asymmetrical unit connected in multiple with said first relay and poled to shunt energy from said one battery away from said first relay.

13. In combination with a section of railway track provided at one end with a track transformer having its secondary winding connected across the track rails and its primary winding energized from a source of unidirectional current over a coding contact operable to cause the induction in said secondary winding of an impulse of relatively high peak voltage each time the coding contact interrupts the connection of said primary winding with said source, said track section having coupled across the track rails at the opposite section end a track relay responsive to high voltage impulses of short duration, a neutral relay having its winding connected in circuit with said secondary winding of said track transformer across the track rails at said one section end, said neutral relay being immune to operation by said high voltage impulses, and a second source of unidirectional current interposed in the coupling of said track relay to the rails at said other section end for energizing said neutral relay, said coupling being arranged to avoid operation of said track relay by energy from said second source.
